CONDENSER

Robert R. Hull, Los Angeles, Calif., assignor to
Engineering Controls, Inc., Los Angeles, Calif.,
a corporation of California

Application February 24, 1947, Serial No. 730,392

10 Claims. (Cl. 257—46)

1

This invention relates to heat exchangers such as condensers, radiators, space heaters, and the like.

A primary object of the invention is to provide an improved heat exchanger or condenser wherein the heat exchanger is divided into two sets of inclined tubes, one of which is adapted to have steam supplied thereto at its lower end and which is in communication with the other set at its upper end so that when steam is supplied to the heat exchanger in small quantities or under light loads it may condense and be deposited in the first set of tubes and flow therefrom counter to the direction of the flow of steam thus effectively preventing freezing of the condensate in the tubes when the heat exchanger is subjected to very cold temperatures or to very cold cooling air. When the supply of steam is increased or the load is increased so that more steam is supplied to the heat exchanger than will condense in the first set of tubes, the excess of steam will pass from the upper end of the first set into the upper end of the second set where further condensation will take place. In this respect the heat exchanger may be regarded as somewhat automatic in that it automatically increases the number of tubes being used to condense the steam in accordance with the amount of steam supplied to the device.

Another object of the invention is to provide a condenser or heat exchanger having the above mentioned characteristics wherein the second set of tubes is arranged behind the first set of tubes with relation to the direction of the flow of cooling air so that although the condensate in the second set of tubes is flowing concurrently with the direction of the steam and may even flow in advance of the steam, danger of freezing in the second set is avoided due to the fact that at the time that the second set of tubes is utilized it is effectively warmed by the air which has been warmed by passing over the first set of tubes.

With the foregoing and other objects in view, which will be made manifest in the following detailed description and specifically pointed out in the appended claims, reference is had to the accompanying drawings for an illustrative embodiment of the invention, wherein:

Figure 1 is a view in side elevation, parts being broken away and shown in section, illustrating a device embodying the present invention;

Fig. 2 is a transverse vertical section through the device shown in Fig. 1;

Fig. 3 is a view similar to Fig. 2 but illustrating a modified form of construction;

Fig. 4 is a view in elevation, parts being illus-

2

trated in section, and illustrating a further modification;

Figures 5 and 6 are sectional views taken respectively on lines 5—5 and 6—6 of Figure 4.

Referring to the accompanying drawings wherein similar reference characters designate similar parts throughout, the improved heat exchanger or condenser may be advantageously used in conjunction with the cooling system of an internal combustion engine wherein the water of the cooling system is maintained at its boiling point. Such internal combustion engines are frequently located where their radiators or condensers are subject to atmospheric conditions well below freezing. It is desirous under such circumstances to utilize only a small portion of the available heat exchange area of the radiator when the engine is operating under light loads and is delivering in the cooling system but a small quantity of steam but to utilize more and more and finally the entire amount of the available heat exchange area as the load increases and more steam is being supplied to the radiator to be condensed therein. In accordance with the present invention the condenser or radiator consists of two sets of tubes which, in the form illustrated in Figs. 1 and 2, are indicated generally at 10 and 11. Each of these sets may consist of an upper bank of tubes and a lower bank although it is possible to construct a suitable radiator wherein each set of tubes consists of but a single bank of tubes and in other instances each set may consist of more than two banks of tubes.

12 indicates a tank that may form a part of or may be connected to the water cooling system of the engine, 13 being a filler opening therefor. In this tank there are suitable partitions 14 and 15 which define a steam passage 16 from the top of the tank 12 to the bottom of the lower inclined set 11. An upper tank 17 closes the upper ends of both sets of tubes and provides for communication between the upper ends of the tubes of the lower set 11 with the upper ends of the upper set 10. The partition 15 constitutes a collecting means for collecting condensate from the upper set 10 and returning the condensate to a drain pipe 18 that returns it to the water space in the bottom of the tank 12, the water level being indicated by the dotted line 19. The construction of the heat-radiating fins that are normally provided between the tubes is immaterial in so far as the present invention is concerned. The operation of the above described construction is as follows:

Steam rising from the water in the bottom of

the tank 12 finds ingress to the steam passage 16 through the aperture 20. During light loads of the engine the volume of steam generated is relatively small. This steam enters the lower ends of the inclined set 11 and flows upwardly therein. The direction of air flow between the tubes in this form of construction may be assumed to be upward and this direction may be induced thermally or created by a fan or blower. When a small amount of steam is supplied to the lower ends of the set of tubes 11, this small amount will quickly condense before the steam progresses any great distance up these tubes. Particularly is this true when the temperature of the cooling air is very low. The condensate which cools on the walls of the tubes of the lower set drains back in a counterflow direction with respect to the flow of steam and is collected by the partition 14 and returned to the water space of the tank 12 through one or more apertures 21. Under these circumstances even if the air passing across the tubes is very cold and is much below freezing, as the condensate is continually flowing back countercurrently to the direction of the flow of steam there is no danger of this condensate freezing in the tubes inasmuch as it flows back out of the tubes as soon as it is deposited. As the load increases and the amount of steam supplied to the tubes increases the steam may progress farther and farther up the tubes of the lower set 11 with the condensate continually flowing back down the tubes which are maintained at a temperature well above freezing by the incoming steam. When the load materially increases, however, the steam will pass through the entire length of the tubes of the lower set 11 without becoming completely condensed therein. The excess of steam may then flow through tank 17 to the tubes 10 of the upper bank and be cooled and condensed therein. The condensate in these upper tubes will flow downwardly therein concurrently with the flow of steam therethrough and, in many instances, in advance of the steam. This condensate is collected by the partition 15 and is returned to the tank 12 through the drain pipe 18. Although the condensate in the tubes of the upper bank may flow ahead of the steam therein, it is to be observed that when these tubes are brought into operation the tubes of the lower set 11 are quite warm. Consequently the cold air flowing across the tubes of the lower set is heated thereby and will serve to warm the tubes of the upper set. In this manner the condensate in the tubes of the upper set is kept from freezing even though it flows therethrough in advance of the steam.

In internal combustion engines, particularly those which employ "vapor phase" cooling or that type of cooling wherein the cooling water is maintained at its boiling point, removal of air and other non-condensable gases from the system is necessary. To this end a vent tube 43 leads into the compartment formed by partition 15 providing an escape of such air and non-condensable gases from the system and it will be appreciated that by placing the vent tube at the outflow end of the second set of tubes through which the vapor passes that the vent tube serves to allow air and non-condensable gases to escape from the system without any material escape of vapor.

In the form of construction illustrated in Fig. 3, there is a tank 25 which may be supplied with cooling water from the engine at its boiling point. In this tank there are partitions 26 and 27 which define a steam passage 28 leading to the lower end of an inclined bank of tubes 29. The upper

end of this bank is in communication with the second bank of tubes 30 which are similarly inclined and which are arranged beneath the bank 29 or behind this bank with relation to the direction of the air flow therebetween. In this form of construction the air may be assumed to be forced or drawn in a downward direction between the tubes. Condensate from the upper bank of tubes 29 is collected between the partitions 26 and 27 and is returned to the water space of the tank 25, the level of the water being indicated by the dotted line 81. Similarly condensate from the lower bank 30 is returned through passage 70 to the water space of the water tank. In this form of construction when a small amount of steam is being delivered to the device this steam enters the lower ends of the tubes of bank 29 and flows upwardly therein until condensed. Under heavy loads where larger amounts of steam are being developed, that steam which does not condense in the upper bank 29 is caused to flow downwardly through the tubes of the lower bank 30. In the upper bank condensate flows downwardly through the tubes in a countercurrent direction with respect to the direction of the steam whereas in the lower bank 30 condensate flows downwardly through these tubes and may flow in advance of the steam. Where only the tubes of the upper bank are being utilized the counterflow of condensate through steam prevents the condensate from freezing even though the cooling air may be extremely cold. When the steam supplied to the condenser increases so that the lower bank 30 is brought into operation, the condensate which flows downwardly through these tubes in advance of the steam is kept from freezing therein due to the fact that the air then passing over these tubes has been adequately heated by the tubes of the upper bank 29. An inlet 44 is provided and leads directly to the tank 25 below the liquid level therein as shown by the dotted lines and an outlet 45 leads directly from tank 25 and communicates with the tank below the liquid level therein.

A vent tube 31 is preferably connected through the partition 27 to the outlet space for the lower set of tubes 30. This vent tube serves to conduct off air and other non-condensable gases that may be introduced into the cooling system. Preferably this vent tube is arranged in advance of the tubes of the upper set so as to be cooled by the air in advance of its being warmed by the tubes of the upper set. Consequently, as this vent tube will be cooled to the greatest extent should any steam tend to rise in the vent tube after having passed through both sets 29 and 30, this steam will be condensed and due to the inclined position of the vent tube the condensate will drain back into the water space of the tank 25.

In the construction illustrated in Fig. 4, the condenser is positioned over the top of an open-topped water jacket on an engine. In this form of construction there is illustrated a first set of tubes 35 which may consist of two banks of tubes that are vertically arranged over the steam space that is immediately above the normal water level indicated by the dotted line 82. The second set of tubes indicated at 36 is in communication with the upper ends of the tubes of the first set through a cover 37. The lower ends of the tubes of the second set drain into a tank 38 from which a pipe 39 leads back to the water space in the water jacket. The vent tube for non-condensable gases is indicated at 40 leading from the tank 38 upwardly to a point adjacent the top of the con-

denser. In this form of construction the air is forced or is induced to flow across the tubes of the first set 35 before traversing the tubes of the second set 36. With this arrangement, as steam rises in the tubes of the first set it will condense therein and the condenser flow downwardly in a countercurrent direction to the direction of the flow of steam. As the load increases and the quantity of steam developed increases, the steam will rise higher and higher in the tubes 35 before becoming condensed. Under heavy loads the steam may not be completely condensed in the tubes 35 and the tubes 36 will then be brought into operation by the excess steam flowing across beneath the cover 37 and into the tubes 36. In these tubes the condensate drains downwardly in a direction concurrently with the direction of steam flow and may flow in advance of the steam. Danger from freezing therein, however, is avoided by reason of the fact that the air serving to cool the tubes 36 has been warmed on flowing across the tubes 35 wherein the condensate flows in a counterflow manner. A filler pipe 46 is provided and the top of the filler pipe is approximately equal to the liquid level within the condenser and this filler pipe being so constructed sets a predetermined maximum level at which the liquid may rise in the condenser when the condenser is filled and this situation is also present in the device disclosed in Fig. 1 since it is obvious that the filler pipe 13 sets a predetermined maximum level at which the liquid within the condenser can rise when the device is filled.

In all of the above described constructions it will be appreciated that the steam is first conducted into a set of tubes that are so arranged that the condensate therein will return in a direction opposite to the direction of the flow of steam. Consequently this condensate, which is warmed by the oncoming steam, is kept from freezing. Under heavy load conditions additional tubes are automatically brought into operation wherein the condensate flows concurrently with the direction of steam flow. These tubes, however, are arranged behind the counterflow tubes so as to be effectively warmed by the heated air that has been heated by the counterflow tubes. Consequently in the tubes of the second set the condensate is maintained against freezing even though it may flow in advance of the steam.

While the invention has been primarily designed as a condenser for condensing steam, it will be readily appreciated by those skilled in the art that it is equally applicable to a heat exchanger or a space heater which may be subject to freezing ambient temperatures. Thus, if used as a space heater under freezing conditions steam may be admitted to the tubes of the first set to warm the air traversing these tubes. If the amount of steam available is relatively small this steam will condense in the tubes of the first set and as the condensate flows in a reverse direction to the direction of steam, danger of its freezing in these tubes is avoided. When the amount of steam available increases the excess may flow into the tubes of the second set but the condensate therein is maintained against freezing due to the warming action of the air which has traversed the heated tubes of the first set before encountering the tubes of the second set.

Various changes may be made in the details of construction without departing from the spirit and scope of the invention as defined by the appended claims.

I claim:

1. A condenser having two sets of tubes at an angle to the horizontal, means enclosing the upper ends of the tubes for communicating the upper ends of the sets of tubes with one another, means enclosing the lower ends of the tubes and extending down below the lower ends of the lower tubes and providing a liquid reservoir, a liquid and vapor inlet for the condenser leading directly to the liquid reservoir below the liquid level therein, a liquid outlet from the condenser leading directly from said liquid reservoir below the liquid level therein, means directing vapor rising from the reservoir into the lower ends of one of the sets of tubes to heat the outside of the same and preventing the vapor from entering the lower ends of the other set of tubes, an air inlet, an air outlet, said sets of tubes being in an air passageway which extends from said air inlet to said air outlet with the outside of the other set of tubes being in an air stream which in passing from said air inlet to said air outlet flows from the outside of said one set of tubes to convey heat from the outside of said one set to the outside of said other set.
2. A condenser as set out in claim 1 in which a filler pipe is provided and communicates with the liquid reservoir and rises upwardly to a point below the lower ends of the lowest tubes.
3. A condenser as set out in claim 1 in which there are means communicating adjacent the outflow ends of said other set of tubes for allowing air and other noncondensable gases to escape.
4. A condenser having two sets of tubes at an angle to the horizontal, one set being arranged above the other set, means enclosing the upper ends of the sets of tubes with one another, means enclosing the lower ends of the tubes and extending down below the lower ends of the lower tubes and providing a liquid reservoir, a liquid and vapor inlet for the condenser leading directly to the liquid reservoir, a liquid outlet from the condenser leading directly from said liquid reservoir, partition means extending only part way into the liquid reservoir for directing vapor rising from the reservoir into the lower ends of the upper set of inclined tubes, whereby the vapor flows through the upper set of tubes to heat the outside of the same and then through the lower set of tubes, a filler pipe communicating with the liquid reservoir and rising upwards to a point below the lower ends of the lower set of tubes, means communicating adjacent the outflow ends of the lower set of tubes for allowing air and other noncondensable gases to escape, an air inlet, an air outlet, said sets of tubes being in an air passageway which extends from said air inlet to said air outlet with the outside of the lower set of tubes being in an air stream which in passing from said air inlet to said air outlet flows from the outside of said upper set of tubes to convey heat from the outside of said upper set of tubes to the outside of said lower set of tubes.
5. A condenser having two sets of tubes at an angle to the horizontal, one set being arranged above the other, means enclosing the upper ends of the tubes for communicating the upper ends of the sets of tubes with one another, walls defining a first chamber enclosing the lower ends of the sets of tubes and extending down below the tubes and providing a liquid reservoir, an inlet leading directly to the liquid reservoir, an outlet leading directly away from the liquid reservoir, walls defining a second chamber contain-

ing the lower ends of the upper tubes and with said second chamber being in communication with said reservoir, walls defining a third chamber enclosing the lower ends of the lower tubes, said third chamber being contained within the first chamber and having vapor inlets in the upper portions thereof whereby vapor from the reservoir may rise and flow into the third chamber through the lower tubes to heat the outside of the same and then through the upper tubes and into the second chamber, an air inlet, an air outlet, said sets of tubes being in an air passageway which extends from said air inlet to said air outlet with the outside of said upper tubes being in an air stream which in passing from said air inlet to said air outlet flows from the outside of said lower set of tubes to convey heat from the outside of said lower set to the outside of said upper set.

6. A condenser as set out in claim 5 wherein there are means communicating with the second chamber for allowing air and other non-condensable gases to escape.

7. A condenser having two sets of tubes at an angle to the horizontal, one set being positioned above the other set, means enclosing the upper ends of the tubes to allow the two sets of tubes to communicate with one another, means enclosing the lower ends of the tubes and extending down below the lower ends of the lower tubes to provide a liquid reservoir, partition means arranged inside said chamber extending completely across the chamber and separating the upper set of tubes from the lower set of tubes and extending downwardly below the liquid level in the reservoir, other partition means forming an upper compartment in the chamber for the upper set of tubes and extending down below the liquid level in the reservoir, means providing a passage from the upper part of the chamber into the upper compartment whereby vapor rising from the reservoir is directed to flow upwardly into the upper compartment into the upper set of tubes to heat the outside of the same, the liquid condensing in the upper set of tubes flowing downwardly between the first partition means and the second partition means to the reservoir, the vapor not condensed in the upper set of tubes allowed to flow through the lower set of tubes and the liquid condensing in the lower set of tubes allowed to flow down into the reservoir, an air inlet, an air outlet, said sets of tubes being in an air passageway which extends from said air inlet to said air outlet with the outside of said lower tubes being in an air stream which in passing from said air inlet to said air outlet flows from the outside of said upper set of tubes to convey heat from the outside of said upper set of tubes to the outside of said lower set of tubes.

8. A condenser as set out in claim 7 wherein there are communicating means adjacent the lower ends of the lower tubes for allowing air and other non-condensable gases to escape.

9. A condenser having two sets of tubes at an

angle to the horizontal, means enclosing the upper ends of the tubes for communicating the upper ends of the sets of tubes with one another, means defining a chamber enclosing the lower ends of the tubes and extending down below the lower ends of the lower tubes providing a liquid reservoir, a liquid and vapor inlet for the condenser leading directly to the liquid reservoir below the liquid level therein, a liquid outlet from the condenser leading directly from said liquid reservoir below the liquid level therein, and means directing vapor rising from the reservoir into the lower ends of one of the sets of tubes to heat the outside of the same and preventing the vapor from entering the lower ends of the other set of tubes, an air inlet, an air outlet, said sets of tubes being in an air passageway which extends from said air inlet to said air outlet with the outside of the other set of tubes being in an air stream which in passing from said air inlet to said air outlet flows from the outside of said one set of tubes to convey heat from the outside of said one set to the outside of the other set.

10. A condenser having at least two tubes at an angle to the horizontal, means enclosing the upper ends of said tubes for communicating their upper ends with each other, said two tubes being serially connected with the lower end of one of said tubes being in communication with a steam inlet whereby steam from said inlet passes upwardly through said one tube to heat the outside of the same, the resulting condensate in said one tube gravitating back to said steam inlet in a counterflow direction whereby said condensate may be heated by the steam entering the lower end of said one tube, an air inlet, an air outlet, said two tubes being in an air passageway which extends from said air inlet to said air outlet with the outside of said other tube being in an air stream which in passing from said air inlet to said air outlet flows from the outside of said one tube to the outside of said other tube to prevent freezing of condensate in said other tube.
